(57) **CLAIM**

The ornamental design for a controller unit as shown and described.

DESCRIPTION

FIG. 1 is a top front perspective view of a controller unit of our claimed design.

FIG. 2 is a bottom rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is top plan view thereof; and,

FIG. 8 is bottom plan view thereof.

The broken lines in the drawings depict portions of the controller unit which form no part of the claim.
